DESIGN FOR AN ENSEMBLE COSTUME

Concetta Jaccarino, New York, N. Y., assignor to
C. H. D. Robbins Co. Inc., New York, N. Y., a
corporation of New York

Application April 14, 1934, Serial No. 51,412

Term of patent 3½ years

To all whom it may concern:

Be it known that I, CONCETTA JACCARINO, a citizen of the United States, residing at New York, county and State of New York, have invented a new, original, and ornamental Design for Ensemble Costume, of which the following is a specification, reference being had to the accompanying drawing, forming a part thereof.

The drawing shows a front view of my design for costume.

The rear of the ensemble costume is of conventional design with the exception of the ruffle at the collar and sleeves which extends entirely about the respective elements.

I claim:

The ornamental design for an ensemble costume, substantially as shown and described.

CONCETTA JACCARINO.
